UNITED STATES PATENT OFFICE.

ROBERT J. ROBINSON AND CYRUS F. COLLINS, OF LINNEUS, MISSOURI.

SICKLE-ADJUSTER.

SPECIFICATION forming part of Letters Patent No. 430,754, dated June 24, 1890.

Application filed March 5, 1890, Serial No. 342,792. (No model.)

To all whom it may concern:

Be it known that we, ROBERT J. ROBINSON and CYRUS F. COLLINS, citizens of the United States, residing at Linneus, in the county of Linn and State of Missouri, have invented 5 a new and useful Roller-Sickle Adjuster, of which the following is a specification.

This invention relates to cutting apparatus for harvesters, and is more particularly a 10 roller-sickle adjuster adapted to be used on the finger-bar in rear of the knife-bar.

The object of the present invention is to provide a very simple means for guiding the said rod in its reciprocation and reducing to 15 a minimum the friction thereon. This object we accomplish by our improved guard, which consists of a block of malleable iron carrying a friction-roller journaled near its front edge, and which block is suitably and adjust- 20 ably connected to the finger-bar, all as will be more fully described hereinafter, and illus- 25 trated in the accompanying drawings, in which—

Figure 1 is a top plan, and Fig. 2 a bottom plan, of a harvester-bar with our improved 30 guide attached thereto. Figs. 3 and 4 are respectively a front and a side view of the guide removed and on an enlarged scale. Fig. 5 is a cross-section on the line 5 5 of

Fig. 1.

Heretofore the bar carrying the knives has been guided by guides having anti-friction rollers above, below, and in rear of such bar, the above being our own inventions; but we 35 are not aware that a guide has been constructed with the details that the present one possesses, whereby the upper and lower rollers are dispensed with and yet all the necessary guiding action is given the rod.

40 Referring to the said drawings, B designates the finger-bar carrying the guards G and suitably supported by the harvester-machine, as will be clearly understood.

R designates the reciprocating knife-bar 45 carrying the knives L, which play within grooves in the guards G in a manner also well understood.

Coming now to the present invention, 1 is a rod connecting the guards G and standards 50 in a plane below the knives L, and this rod, with the front edge of the finger-bar B, forms

a slot 2, in which the knife-bar R plays back and forth. The rod 1 also braces the guards against lateral play and keeps the parts rigidly in proper relative position.

55

3 designates our improved guide, whose body has rearwardly-extending ends 4, provided with slots 5, by means of which it is bolted to the upper side of the finger-bar B, and may be adjusted forward as the knife-bar R wears, to take up all lost motion. At the center of its front edge the guide 3 has a forwardly-projecting tongue 5', which passes over the knife-bar R when the parts are in proper position, and beneath which said rod 60 slides freely. This tongue prevents the knife-bar R from rising as it reciprocates in its slot 2, and it is provided in its length with a transverse groove 6, beneath which 65 pass the heads of the rivets or bolts 7, that fasten the knives L to the knife-bar R, all as clearly shown in the accompanying drawings.

Projecting downwardly from the body of the guide 3 at points about beneath the sides of the tongue 5' at its rear end are arms 8, 70 which fit in a notch 10 in the front edge of the finger-bar B, and their lower ends are united, as at 8', and continued forwardly by an independent tongue or lip 9, that is secured in place by the pin 12 and passes under 75 the knife-bar R, carrying the knives L, above which said rod slides freely. A friction-roller 11 is mounted upon a pin 12, which is seated at its ends above and below the roller in the united portion 8' of the arms 8, and in the 80 tongue 5', as shown, and this roller bears against the rear edge of the knife-bar R, whereby the latter is pressed forward against the rod 1 and the resistance offered in the 85 act of mowing and kept in its proper position. 90 The entire guide is preferably cast in one piece, except, of course, the lip 9, the pin, and the roller, and can be applied to and removed from the cutter-bars of harvesters now on the market with but very slight changes in their 95 structure.

We claim as the salient points of our invention:

1. In a harvester cutting apparatus, the combination, with the reciprocating knife-bar R and the finger-bar B, having a notch 10 in its front edge, of the guide 3, bolted upon

- the upper face of said finger-bar, a tongue 5', extending from the upper face of said guide over the knife-bar R, arms 8, extending downwardly from said guide and fitting 5 the notch in the finger-bar B, and anti-friction roller 11, pivoted on a vertical pin 12 between said arms, said roller bearing against the rear edge of the knife-bar R, as and for the purpose set forth.
- 10 2. In a harvester cutting apparatus, the combination, with the reciprocating knife-bar R and the finger-bar B, having a notch 10 in its front edge, of the guide 3, adjustably secured to the upper face of said finger-bar, a tongue 5', extending from the upper face of said guide over the knife-bar R, arms 8, extending downwardly from said guide through the notch in the finger-bar, a lip 9, connected 15 to the lower ends of said arms and extending 20 forwardly therefrom, a pin 12, connecting said tongue and lip, and a friction-roller 11, journaled on said pin between said arms, said roller bearing against the rear edge of the knife-bar R, as and for the purpose set forth.
- 25 3. In a harvester cutting apparatus, the combination, with the reciprocating knife-bar R, of the guide 3, bolted upon the upper

face of the finger-bar, a tongue 5', extending from the upper face of said guide over the knife-bar R, arms 8, extending downwardly 30 from said guide, a lip 9, extending forwardly from said arms below said knife-bar, and an anti-friction roller 11, pivoted on a vertical pin 12 between said arms, said roller bearing against the rear edge of the knife-bar R, as 35 and for the purpose set forth.

4. The guide 3, made of a single piece, and comprising the body adapted to be bolted upon the upper face of the finger-bar, the tongue 5', extending from the upper face of 40 said body, arms 8, extending downwardly from said guide and united, as at 8', and an anti-friction roller 11, pivoted between said arms 8, the whole adapted for use substantially as set forth.

In testimony that we claim the foregoing as our own we have hereto affixed our signatures in presence of two witnesses.
